MOLD FOR A PLASTIC RING HAVING AN ANNULUS AND A MOTIF
William M. Lester, Mountainside, N.J.
Application October 5, 1946, Serial No. 701,446
2 Claims. (Cl. 18—42)

1
The invention herein disclosed relates to the molding of thermo-plastic material and more particularly to a die for molding a ring having an annulus and a motif.

In the manufacture of rings from thermo-plastic material, such as finger rings, for example, that consist of an annulus and a motif, it has been the practice, prior to this invention, to mold the annulus and motif separately. The two parts are then secured together with cement.

Another object of the invention is to provide a die for molding a thermo-plastic ring having an annulus and a motif, in a single piece. A further object of the invention is to provide a die for the purpose mentioned that is simple in construction and in which the motif cavity may be changed without the necessity of making an entire new die.

The foregoing objects and certain advantages that will hereinafter appear are realized in the dies and the ring illustrated in the accompanying drawing and described in detail below, from which description a clearer understanding of the invention may be had.

The drawings include:

Fig. 1 which is a fragmentary, sectional plan of a die in the closed position thereof;

Fig. 2 which is a like, fragmentary, sectional plan of the same in the open position thereof;

Fig. 3 which is a fragmentary, sectional plan of a modified die in the closed position thereof;

Fig. 4 which is a like, fragmentary, sectional plan of the same in the open position thereof;

Fig. 5 which is a fragmentary, sectional plan of another modification of the die in the closed position thereof;

Fig. 6 which is a like, fragmentary, sectional plan of the same in the open position thereof;

Fig. 7 which is a plan of a ring comprehended within the invention; and

Fig. 8 which is an elevation of the same.

The ring illustrated in Figs. 7 and 8 of the drawing and shown in certain of the other figures consists of a single piece of molded, thermo-plastic material. This ring includes an annulus 1 and a motif 2. The motif, which may be of any desired design, is wider and longer than the thickness of the annulus 1. The ring is molded as a single piece of thermo-plastic material in a three part die such as any one of the dies illustrated in Figs. 1 to 6.

The die of Figs. 1 and 2 includes an injection half or part 3 and an ejector half or part 4. As is common and well known in the art, the injection part of the die is mounted stationary on

2
the injection molding machine. The ejector half of the mold or die is mounted on the movable die holder of the machine and is moved toward and away from the injection half to close and open the die.

In the die illustrated in Figs. 1 and 2, the injection half 3 of the die has a cavity 5 formed therein that is complementary to the desired shape of the motif, such as the motif 2. This cavity for the motif is wholly within the injection half of the die and terminates in a flat surface at the plane of the parting line of the two halves of the die. That is to say, the surface of the ejector half of the die closes the cavity for the motif.

The ejector half of the die has a recess 6 formed therein and in which two die parts 7 and 8 are slidably mounted. The side walls 9 and 10 of the recess 6 are inclined to a central plane parallel to the line of movement of the ejector half of the die, and converge. The die part 7 has an inclined side wall 11 complementary to and engaging the inclined wall 9 of the recess 6, and a straight surface 12 parallel to a vertical plane containing the line of movement of the ejector half of the die. In like manner, the die part 8 has an inclined surface 13 complementary to and engaging the inclined wall 10 of the recess 6, and a straight surface 14 opposed to the straight surface 12 of the die part 7. The inclined surface 11 of the part 7 is held in engagement with the surface 9 by a pin 15 extending into an elongated, inclined slot 16 in the part 7. A similar pin 17 extends into an elongated, inclined slot 18 in the part 8. The slots 16 and 18 are parallel to the walls 9 and 10 respectively.

Each of the die parts 7 and 8 contain a part of the cavity for the annulus. One part 19 of the annulus cavity is formed in the surface 12 of the part 7, adjacent the end thereof. The other part 20 of the annulus cavity is formed in the surface 13 of the part 8, adjacent the end thereof. It is to be noted that the annulus cavity cuts through the end surfaces 21 and 22 of the parts 7 and 8 respectively.

In the closed position of the die (Fig. 1), the cavities 19 and 20 form an annular cavity which through the surfaces 21 and 22 communicate with the motif cavity 5 in the injector half of the die. Thus, a mold cavity is formed which is complementary to a ring, a finger ring, for example, that includes a motif and an annulus. Into this cavity through a gate (not shown) thermo-plastic

material is injected to form a ring, such as the ring shown in Figs. 7 and 8.

After the mold cavity has been filled and the thermo-plastic solidified therein, the ejector half 4 of the die is moved away from the injection half 3. The motif 2 moves with the ejector half out of the cavity 5. When the ejector half 4 of the die has moved a predetermined distance away from the injection half, the parts 7 and 8 are engaged by stationary ejector pins 23 and 24 respectively, which extend through openings in the ejector half of the die. Upon further movement of the ejector half of the die, the ejector pins hold the parts 7 and 8 stationary and the pins 15 and 17, acting in the slots 16 and 18 respectively cause the parts 7 and 8 to separate, as shown in Fig. 2. The ring is thus free to drop, or be removed from the die. As the ejector half moves to the closed position, the parts 7 and 8, by contact with the surface of the injection half 3, are caused to move into the recess 6, and by virtue of the inclined surfaces 9 and 11, and 10 and 13, the die parts are moved together.

In the die illustrated in Figs. 3 and 4, the cavity 25 for the motif is formed in a sliding core 26 that is moved at right angles to the relative movement of the injection half or part 27 and the ejector half or part 28. The injection half 27 is cut away at 29 and the injector half is cut away at 30 so that in the closed position of the die, a recess is formed in the die for the sliding core. The cavity 30, for the annulus is formed in part in the injection half 27 and in part in the ejector half 28. Each part of the annulus cavity extends through the surfaces 31 and 32 of the injection half 27 and the ejector half 28 respectively, which contact the end surface of the core 26 in the closed position of the die. Thus in the closed position of the die, the motif cavity 25 and the annulus cavity communicate and form a cavity that is complementary to a ring. When the die is opened, the core 26 slides at right angles to the line of movement of the ejector half 28. The ring formed may drop or be otherwise removed from the die.

Two sliding cores or die parts 33 and 34 are utilized in the die illustrated in Figs. 5 and 6. In this die, the motif cavity 35 is formed in the surface 36 of the injection half 37 of the die. The ejector half 38 of the die has a plane surface and the sliding cores 33 and 34 move between the injection and ejector halves of the die at right angles to the line of movement of the ejector half. A part 39 of the annulus cavity 40 is formed in the end surface of the core 33 and the other part 41 of the annulus cavity is formed in the end surface of the core 34. These cores are moved toward and away from each other in a manner well known in the art to bring the end surfaces together and to separate them. The part 39 of the annulus cavity extends through the side wall 42 of the core 33, and the part 41 extends through the side wall 43 of the core 34. In the closed position of the die (Fig. 5), the end surfaces of the cores are in contact and centered with respect to the motif cavity 35. Thus, a single cavity is formed complementary to a finger ring having a motif and an annulus. When the ejector half of the die moves away from the injection half, the cores slide to separate the end surfaces thereof. The die is thus opened and the ring formed may drop, or be removed from the die as is evident from Fig. 6.

A ring made as above described and consisting of a single piece of molded, thermo-plastic material has many advantages. It is comparatively inexpensive since no assembly operations are required, and it is superior in appearance. This latter is particularly true when the ring is made from a transparent or translucent plastic because there is no joint between the annulus and the motif to detract from the appearance of the ring.

A die embodying the invention, such as the dies illustrated in the drawing and described above, is readily made because of the simplicity of the construction. In addition, for a given size ring, the motif may be changed by merely changing the die part containing the motif cavity. Alternatively, different sized rings may be made with the same motif by changing the die parts in which the annulus cavity is formed. These are important advantages as such rings are novelties, made in several sizes and with a great variety of motifs.

It will be obvious that various changes may be made by those skilled in the art in the dies and the ring illustrated in the drawing and described in detail above within the principle and scope of the invention as expressed in the appended claims.

I claim:

30 1. A die for molding a ring having an annulus and a motif from thermo-plastic material which die consists of a plurality of separable parts, each part having a portion of the mold cavity therein and including two parts relatively movable at right angles to the plane of the annulus cavity, and a third part having the cavity for the motif therein, and means for effecting relative movement between said first mentioned two parts and said third part parallel to the plane of the annulus, the relative separating movement of said three parts being such that a ring molded in the cavity may drop from the mold.

45 2. A die for molding a ring having an annulus and a motif from thermo-plastic material which die includes a normally stationary part having a mold cavity for the motif therein, a separable part movable toward and away from said stationary part, two movable parts carried by said separable part each having a portion of the cavity for the annulus therein and being movable relative to the separable part and towards and away from each other, and means for effecting relative movement of the said two movable parts upon separating movement of the separable part to position the said two movable parts to drop a ring molded in the mold cavity.
